Inventor:

Catherine O'Hara.

UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S POLONAISE.

SPECIFICATION forming part of Design No. 14,415, dated November 13, 1883.

Application filed September 26, 1883. Term of patent 3½ years.

To all whom it may concern:

Be it known that I, CATHERINE O'HARA, of the city, county, and State of New York, have invented and produced a new and original Design for a Pattern of a Lady's Polonaise, numbered 8,866; and I do hereby declare that the engraved prints accompanying this specification convey to any one accustomed to using paper patterns a clear understanding of how a garment made up by the pattern will appear.

The design combines a closely-fitted front that is closed from the neck to some distance below the waist-line, and a closely-fitted back having its skirt amplified by fullness at the

lower ends of its seams, both sections being 15 draped high at the sides by plaits to fall in deep oval draperies. Coat-sleeves and a standing collar are added.

What I claim as my invention, and desire to secure by Letters Patent, is—

The design for a lady's polonaise, as shown in the engraved prints accompanying this specification.

CATHERINE O'HARA.
